UNITED STATES PATENT OFFICE.

EDMOND KUHN, OF EAST ORANGE, NEW JERSEY.

GAME APPARATUS.

No. 818,895.

Specification of Letters Patent.

Patented April 24, 1906.

Application filed September 13, 1904. Serial No. 224,280.

To all whom it may concern:

Be it known that I, EDMOND KUHN, a citizen of the United States, residing at East Orange, in the county of Essex and State of New Jersey, have invented new and useful Improvements in Game Apparatus, of which the following is a specification.

This invention relates to a game, toy, or amusement device; and the invention resides in the novel features of construction set forth in the following specification and claims and illustrated in the annexed drawings, in which—

Figure 1 is a face view of the game device embodying this invention. Fig. 2 is a view like Fig. 1, the dial and hands having been removed. Fig. 3 is a view showing the stop and releasing device. Fig. 4 is a section through the stem and center of the device. Fig. 5 shows a view like Fig. 3, but with the stem depressed or forced inward. Fig. 6 is a face view of a modification. Fig. 7 is a sectional view of Fig. 6. Fig. 8 is a face view of another modification. Fig. 9 is a sectional view of Fig. 8.

In the drawings is shown a case or housing *a*. It can be made in form of a watchcase or pocket device, but not necessarily so. The button *b* has a stem *c*, and a spring *d* tends to hold or move the stem outward. This stem extends outside the case and has a feather or sliding connection with winding-wheel *e*, forming part of or engaging the winding-train of the drum or spring *f*. The rotation of the button or stem rotates the winding-train or winds up the spring; but the stem can have a certain longitudinal play independent of pinion *e*.

If the stem is pressed against the tension of spring *d*, Fig. 5, and then released, the spring will restore the stem to its outward or normal position. This stem when depressed will actuate the anchor *g* of the stop and releasing device and allow the wheel *h* to snap or turn a distance of one of its teeth under the influence or tension of the motor or main spring *f*. This wheel is shown geared to the spring or drum and having four teeth—that is, the wheel makes a quarter of a turn at each actuation of the anchor; but of course another number or division of teeth can be chosen for the wheel. The anchor is fulcrumed or pivoted at *i*, and its play is limited by a suitable stop *k*, such as a pin-and-slot connection.

The staff or spindle *m* of the toothed wheel

carries a driver or star wheel *o*, Fig. 2, which partakes of the step-by-step movement of the toothed wheel. As this driving-wheel snaps or swings about for one step the points thereof engage the hub portions *p* of fly-wheels or disks *q*. These hub or contact portions are made of or provided with soft material, as rubber or felt, or faced or prepared to give a hold or friction contact to the projecting part of the driving-wheel as it flies past the hub. By such driving means an impulse is given to the disks or fly-wheels, and as each disk rotates more or less its staff *r*, with the hand *s* carried thereby, rotates, and on coming to rest the hands will respectively point to some graduation or mark. In Fig. 1, for example, are shown dice-faces *t*, and as the hands respectively come to rest at various faces or points a notation can be made.

The operation of the device is simple. By turning the stem the device is wound up. By depressing the stem the releasing-anchor *g*, pressed by spring *2*, is actuated, and the driving mechanism gives its impulse or imparts motion. As the index or marks come to rest at various points, the result can be noted according to a prescribed or voluntary rule arranged for the game.

In Fig. 1 the indexes *s* are shown movable and the marks or notations are fixed or placed on a dial. The indexes and marks can, however, be made movable with respect to one another in different ways. In Fig. 6 is shown a fixed index or pointer plate *s'*, and the notations *t'* are shown as disks on the rotary spindles *r*. In Fig. 7 the rotary notations are covered by a plate *u*, having sight-openings. Such modifications are of course included in the invention, and the device can be made in a variety of ways or forms without departing from the invention.

The stem *c* forms a simple means for actuating the anchor, which is returned by spring *2* on the release of the stem. The marks or notations can be made in a variety of ways, or colors, pictures, or other figures or illustrations can be employed as called for. The spindles *r* being independent from one another will each come to rest at some individual point, which varies at different times. Such independently-rotatable spindles can of course be arranged in any suitable series or number.

The contact portion of the fly-wheel can be readily formed of a rubber ring slipped

onto the hub or of a rubber disk forming the hub *p*.

What I claim as my invention, and desire to secure by Letters Patent, is—

- 5 1. A game apparatus comprising a loosely-mounted index having a staff with a contact portion, a driving-wheel with a shaft mounted parallel to the staff of the index and having projections to engage the contact portion 10 of the staff of the index when the driving-wheel rotates, a spring for actuating the driving-wheel, a releasing and stop device for the driving-wheel, and a stem having longitudinal motion to oscillate the releasing and 15 stop device and being made rotary and having a gear connection with the spring to wind the latter, said releasing and stop device and spring being all located in planes parallel with the plane of the driving-wheel 20 to form a compact structure.
2. A game apparatus comprising a series of independently-rotatable spindles grouped about a common center point, a driver for giving an impulse to the spindles, a spring 25 for the driver and a releasing device having a stop for the driver, said driver consisting of a wheel rotatable about said center point, and normally out of contact with the surrounding group of spindles and provided with 30 projections made to momentarily contact with the spindles as the driver rotates.
3. A game apparatus comprising rotatable spindles, a driver made to contact with and rotate the spindles, a spring for rotating the driver, a winding-wheel for the spring, a releasing device and stop, and a rotatable and longitudinally-movable stem having gear connection with the winding-wheel and extended into contact with the releasing device.
- 40 4. A game apparatus comprising an index

with a fly-wheel having a hub provided with a contact portion of soft material, and a star-wheel adapted to revolve and engage the contact portion to rotate the fly-wheel and 45 index, said star-wheel being made to rotate about a fixed axis and being normally out of contact with the hub, the projections or points of the star being of such size or diameter as to extend to and contact with the hub 50 as the star-wheel rotates.

5. A game apparatus comprising a dial and indexes, fly-wheels connected with the indexes, a star-wheel for giving an impulse to the fly-wheels, a spring connected to the star-wheel, a releasing device having a stop and a stem made to engage the releasing device and having a gear connection with the spring.

6. A game apparatus comprising a case, a spring in the case, a winding-gear for the spring, a star-wheel actuated by the spring, a releasing and stop mechanism for the star-wheel, a stem slideable through the winding-gear and made to contact with the releasing and stop mechanism and rotatable for rotating the gear to wind the spring, a set of spindles with fly-wheels and hubs independent of one another and grouped about the star-wheel, and indexes carried by the spindles, said star-wheel being normally out of contact with the hubs but having its points of such diameter or reach as to contact with the hubs when the star-wheel rotates.

In testimony whereof I have hereunto set 75 my hand in the presence of two subscribing witnesses.

EDMOND KUHN.
